BY
Richard B. Owen ATTORNEY.

UNITED STATES PATENT OFFICE.

JOHN HALVERSON, OF MADISON, WISCONSIN, ASSIGNOR OF ONE-HALF TO CHARLES E. FRIDAY, OF MADISON, WISCONSIN.

SKATE.

Application filed July 30, 1921, Serial No. 488,650. Renewed February 20, 1924.

To all whom it may concern:

Be it known that I, JOHN HALVERSON, citizen of Norway, residing at Madison, in the county of Dane and State of Wisconsin, 5 have invented certain new and useful Improvements in Skates, of which the following is a specification.

This invention relates to skates and has for its principal object to provide a device of this nature especially useful for younger folks which will be of extremely simple, durable and inexpensive construction, one which is efficient and reliable in operation and well adapted to the purpose 15 for which it is designed.

Another object of the invention is to provide a stirrup for the skate which may be easily assembled and attached to the skate and will be adjustable in relation thereto so 20 as to fit the shoe of the wearer.

Additional objects of the invention will appear in the following specification, in which the preferred form of the invention is disclosed.

25 In the drawing:—

Figure 1 is a side elevation of the skate.

Figure 2 is a top plan view thereof, and

Figure 3 is a section taken on the line 3—3 of Figure 1 looking in the direction 30 of the arrow.

Referring to the drawing in detail it will be seen that the skates each consist of an elongated body 1 which is provided upon its under edge with the runner 2 having the 35 rear extension 3 which is suitably fastened to the rear end of the body 1 and the front extension 4 which is curved over and extends around the forward end and over the front portion of the upper side of the body 40 1, as at 4' and is held in place by any suitable means.

The stirrup used in connection with this skate consists of the toe plate 5 and heel plate 6. The toe plate is provided with the 45 depending parallel spaced ears 6' which straddle the body 1 and prevent transverse movement of the toe plate. This toe plate is provided with an elongated slot 7 for receiving a set screw 8 whereby the toe plate 50 may be adjusted longitudinally of the body 1. The screw extends into the body portion 1 and through a nut 8' embedded in the body portion as clearly seen in Figure 1. A pair of apertured lugs 9 extend from the

sides of the toe plate and receives suitable 55 links 10 whereby a strap 11 may be attached thereto for receiving the forward portion of the shoe and foot of the wearer. A wear plate 18 as well as the heel plate 6, is secured to the top face of the body portion 60 by a bolt 19 and screw 20. The bolts 19 extend through the runner 2 to assist in fastening it to the body portion and opposite ends of the bolts are upset as shown to be flush with the runner and the plates 18 and 6. 65 It will be seen that the toe plate is adapted to slide for adjustment upon the wear plate 18 thereby reducing wear upon the body portion 1. This wear plate is of course apertured to permit the passage of the bolt 70 8 into the body portion.

The heel plate 6 is provided with a pair of side upwardly extending parallel spaced ears 13 and a rear ear 14 and these ears 13 and 14 are suitably connected to a flexible 75 strip 15 which is adapted to encase the rear portion of the shoe and is held in engagement thereto by means of a strap 16 and buckle 17.

From the foregoing description, taken in 80 connection with the accompanying drawings, the construction and operation of the invention will be readily understood without a more extended explanation.

Various changes in form, proportion, and 85 in the minor details of construction may be resorted to without departing from the principle or sacrificing any of the advantages of the invention as defined in the appended claim. 90

Having thus described my invention, what I claim as new and desire to secure by Letters Patent, is:—

A skate comprising an elongated body, a nut embedded in said body, a wear plate covering said nut and having an opening to align with the opening in the nut, a toe plate slidably mounted upon said wear plate and being equipped with a slot, and a screw 95 extending through the slot, wear plate and nut for retaining said toe plate in adjusted position. 100

In testimony whereof I affix my signature in presence of two witnesses.

JOHN HALVERSON.
